ESCROW BUCKET AND COIN GUIDE
Peter Katz, Livingston, and Menashe Bromberg, West Orange, N.J., assignors, by mesne assignments, to Automatic Canteen Company of America, Chicago, Ill., a corporation of Delaware

Filed Apr. 10, 1961, Ser. No. 101,926
6 Claims. (Cl. 194—2)

Our invention relates to an escrow bucket and coin guide and more particularly to an improved escrow bucket and coin guide construction for use with a merchandising machine which is adapted to give change.

As the number of different kinds and brands of merchandise dispensed by a merchandising machine in response to the deposit of various sums representing respective price increases, it becomes important that the merchandising machine be adapted to give change. There are known in the prior art coin mechanisms which are adapted to give change when a sum in coins in excess of the purchase price of a selected article is deposited in the machine. Not only should the mechanism give change, but also it is desirable that coins of the denomination given in change which are deposited in the machine in order to make a purchase be added to the supply of coins available to be given in change.

In some change making mechanisms of the prior art, coins of the denomination given in change which are deposited in the machine are retained on edge on a guide member leading to the change coin tube. Coins of other denominations deposited in the machine are held in escrow by a suitable means such, for example, as an escrow bucket. When a purchase has been made, coins of the denominations given in change are permitted to move into the change coin tube and the escrow bucket is actuated to permit the coins to fall into the coin box. If for any reason the customer desires the return of deposited coins before a selection is made, he can actuate a coin return mechanism which causes all coins which have been deposited in the machine to be returned.

While the mechanisms of the prior art described above function satisfactorily for the most part, they embody a number of defects. The coin guide which receives coins of the denomination given in change and which directs them to the coin change tube when a purchase is made must be sufficiently wide to permit the passage therealong of a newly minted coin. We have discovered that, owing to this fact, two thin coins supported to edge on this guide may overlap and cause jamming of the coin mechanism.

The coin mechanisms of the prior art described above employ an escrow bucket of the "clam-shell" type in which the two sides of the bucket are pivoted at the top thereof. When a purchase is made, one of the two walls is moved away from the other to permit the coins to fall to the coin box. When the coins are to be returned, the other wall of the bucket is moved to permit the coins to fall to a chute which directs them to a return slot. The difficulty which has been encountered with a mechanism of this type is that in operation of the bucket when an actuated wall returns to its initial position a coin may be trapped between the lower edges of the two walls so that a coin either is not accepted or is not returned to the customer, both of which results clearly are undesirable.

2

We have invented an improved escrow bucket and coin guide construction which overcomes the defects of mechanisms of the prior art described above. Our improved escrow bucket and coin guide holds only a single coin of the kind given in change on edge on a guide for movement into the change coin tube when the coins are accepted. It thus obviates the possibility that two thin coins of the kind given in change will overlap and jam the mechanism. We so arrange our escrow bucket that the possibility of a coin being trapped between the sides of the bucket as they return to their normal relative position is obviated. We provide means for moving one of the shelf walls and the movable section of the coin guide supporting the single coin of the kind given in change as a unit to return deposited coins to the customer. When the coins are to be accepted, the other wall of the guide moves to permit the coins to fall to the coin box.

One object of our invention is to provide an improved escrow bucket and coin guide which overcomes the defects of coin handling assemblies of the prior art.

Another object of our invention is to provide an escrow bucket and coin guide which obviates the possibility that two deposited coins intended to replenish the supply of change will overlap to jam the mechanism.

A further object of our invention is to provide an escrow bucket and coin guide in which there is no danger of a coin being trapped between the edges of the escrow bucket walls.

A further object of our invention is to provide an escrow bucket and coin guide in which a movable section of the coin guide which directs a coin to the change tube and a wall of the coin bucket moves as a unit to return coins to a customer.

Other and further objects of our invention will appear from the following description.

In general our invention contemplates the provision of an improved escrow bucket and coin guide in which one of a pair of co-operating escrow bucket walls is pivoted adjacent its top and the other of the walls is pivoted adjacent its bottom. We form one of the walls as an integral part with a movable section of the coin guide leading to the change tube. When a purchase is made, one of the walls is moved to permit deposited coins to drop into the coin box and the coin supported on the movable section of the coin guide is permitted to move into the change tube. When the coin return mechanism is operated, the escrow bucket wall carrying the movable guide section is moved to cause all the coins to be returned to the customer.

In the accompanying drawings which form part of the instant specification and which are to be read in conjunction therewith and in which like reference numerals are used to indicate like parts in the various views:

FIGURE 1 is a side elevation of our escrow bucket and coin guide and its associated structure.

FIGURE 2 is a sectional view of our escrow bucket and coin guide taken along the line 2—2 of FIGURE 1 and drawn on an enlarged scale.

FIGURE 3 is a perspective view of the operating parts of our escrow bucket and coin guide removed from their mountings to illustrate their operation of the parts to accept coins when a purchase is made.

FIGURE 4 is a perspective view of the operating parts of our escrow bucket and coin guide removed from their

mountings to illustrate the operation of the parts when deposited coins are returned to the customer.

Referring now to FIGURE 1 of the drawings, our escrow bucket and coin guide forms part of a coin mechanism, indicated generally by the reference character 10, having a main supporting plate 12 formed with side flanges 14 and 16 having lateral extensions 18 and 20. In a manner known to the art, the support plate 12 carries a coin separator and slug rejector, indicated generally by the reference character 22, which separates coins deposited in a coin slot 24 according to the denomination while rejecting slugs. After having been separated, coins from the slug rejectors 22 pass through a totalizer mechanism, indicated generally by the reference character 26, which in a manner known to the art establishes a credit corresponding to the sum deposited and releases operating mechanisms corresponding to articles at least the purchase price of which has been deposited.

Coins leaving the totalizer mechanism 26 enter our coin guide and escrow bucket mechanism, indicated generally by the reference character 28. Let us assume by way of example that the coin mechanism with which our escrow bucket and coin guide is to be used is adapted to handle quarters, dimes, and nickels. Assume further that the mechanism is to give change in nickels as required. Nickels leave the totalizer mechanism 26 along the path indicated by the broken line arrows in FIGURE 1 while dimes and quarters leave the mechanism 26 along a path indicated by the dot-dash arrows in FIGURE 1. The first nickel leaving the totalizer 26 is guided to a position at which it rests on a movable coin shelf or guide portion 30 which is normally retained in the position shown in FIGURE 1 by a means which will be described hereinafter. In the course of its movement, this first nickel passes by a feeler 32 disposed in the path of the nickel passing to the movable shelf 30. We mount the feeler 32 on a shaft 34 supported between a central wall 36 of the coin guide mechanism 28 and an outer guide wall 38 secured to the wall 36 in spaced relationship thereto by means of screws or the like 40. We mount a counterweight 42 on shaft 34 for movement therewith normally to cause the finger 32 to occupy the position shown in FIGURE 1. To ensure that a nickel entering the mechanism 28 strikes the finger 32 at a point closely adjacent to the shelf 34, we mount a coin guide member 44 on the wall 36. A coin entering the mechanism 28 is guided by the portion 44 along a path such that it strikes finger 32.

As the first nickel entering the mechanism 28 pivots the finger 32 in a clockwise direction as viewed in FIGURE 1, it moves to a position at which it rests on the movable section 30. This nickel is retained on the movable shelf section by means of a stop 46 carried by an arm 48 supported on a hinge 50 on the back of the support plate 12 and normally urged by a spring to a position at which the stop 46 extends through an opening 54 in plate 36 to intercept a coin such as a nickel rolling down the movable chute portion 30.

When a purchase is made in a manner to be described hereinafter, stop 46 is moved out of the path of the nickel on section 30 and the nickel rolls along a stationary shelf section 55 carried by the plate 36 until it falls into a change coin tube 56 carried by the frame 10. We provide our mechanism with a feeler arm 58 pivotally supported on a pin 60 carried by the outer wall 38. A feeler 62 on the end of arm 58 is adapted to sense the presence of a full supply of change coins in the tube 56. When the tube 56 is full, a nickel rolling down the shelf portion 54 toward the tube engages feeler 62 to pivot arm 58 in a clockwise direction as viewed in FIGURE 1. A link 64 pivotally supported on a pin 66 on the arm 58 normally rests on a lug 68 on the arm 58. Movement of the link 64 in a counter-clockwise direction is limited by the interengagement

of a lug 70 on the arm 58 and an offset 72 on the link 64. When, in response to the presence of a full supply of change coins in the tube 56, arm 58 rotates in a clockwise direction as viewed in FIGURE 1, link 64 moves in a clockwise direction to a position at which a stop 76 on the end of the link is in a position at which it blocks an offset lug 78 carried by an arm 80 supported by shaft 34 for rotation therewith. Thus when a full supply of change coins is contained in tube 56, shaft 34 cannot rotate owing to the position of stop 76 and a coin such as a nickel entering the mechanism 28 and striking finger 32 cannot rotate the finger but is directed to the right as viewed in FIGURE 1 to pass below guide portion 44 and into the escrow bucket indicated generally by the reference character 82.

Referring now to FIGURES 1 and 2 the escrow bucket 82 includes a first wall 84 rotatably supported on respective stub shafts 86 and 88 carried by a plate 90 secured to a rib or divider 92 by means of a screw 94 and carried by the wall 36. It will be seen that the movable shelf portion 30 is formed integrally with the wall 84.

We pivotally mount the other wall 96 of the escrow bucket 82 on a pair of pivots 98 and 100. Shaft 98 is carried by a plate 102 secured to a boss 104 on the support plate 36 by a screw or the like 106. Shaft 100 is disposed in a bearing 108 formed in the wall 36.

From the structure thus far described, it will be apparent that the wall 84 of our escrow bucket is mounted for pivotal movement adjacent its lower end while the wall 96 is mounted for pivotal movement adjacent its upper end. We form the lower end of the wall 96 with bifurcations or fingers 110 adapted to move into openings 112 formed in the lower end of wall 84 between shafts 86 and 88. In a manner to be described hereinafter, walls 84 and 96 normally are urged to relative positions at which fingers 110 bear against the upper ends of the openings 112 as viewed in FIGURES 1 and 2.

Referring to FIGURE 1, a housing 114 carried by the frame 10 slidably supports a coin return rod 116 adapted to be actuated by a knob 118. We pivotally mount a coin return bellcrank 120 on a shaft 122 carried by plate 12. One end 124 of bellcrank 120 is disposed between a pair of pins 126 and 128 carried by rod 116. We form the end 130 of bellcrank 120 with a slot 132 adapted to receive a pin 134 carried by the coin return link 136.

Referring now to FIGURES 1 and 4, a spring 138 connected between a pin 140 on the link 136 and a pin 142 on a second link 144 provides a resilient driving connection between the links 136 and 144. When a customer wishes the return of deposited coins before he had made a purchase, he pulls the knob 118 to the left as viewed in FIGURES 1 and 4 to pivot bellcrank 120 in a clockwise direction to urge link 136 downwardly and to move the link 144 downwardly through the medium of spring 138. When the link 144 moves downwardly, a roller or pin 146 carried by the link and extending through a wall 12 engages the lower end of a slot 148 formed in a slide 150 supported for vertical movement on a pair of pins 152 and 154 carried by the wall 36. A spring 156 supported by a pin 158 on the wall 36 bears between a boss 160 carrying pin 152 and a lug 162 formed on the slide 150 normally to urge the slide to a position at which the lower ends of a pair of slots 163 and 165 engage pins 152 and 154. A slot 164 formed in an offset end 166 on the slide 150 receives a pin 168 carried by a crank arm 170 rotatably supported on a shaft 172 carried by wall 36. From the structure just described, it will be apparent that when slide 150 moves downwardly under the action of bar 144, crank 170 pivots in a counterclockwise direction as viewed in FIGURE 4. The bifurcated end 174 of crank 170 receives a pin 176 carried by a crank 178 secured to shaft 88 for rotation therewith. Thus when crank 170

rotates in a counterclockwise direction in the manner described, shaft 88 is driven to move wall 84 and the movable coin shelf portion 30 to the broken line position shown in FIGURE 4 to permit a nickel on the movable shelf portion and the coins in the bucket 82 to fall downwardly and out through an opening 180 formed by boss 92 and by a guide 182 to a chute 184 which guides the coins to a suitable coin return opening (not shown) at which they are received by a customer.

Referring now to FIGURES 1 to 3, the operating mechanism of a machine with which our escrow bucket and coin guide is used may include a pull rod 186 slideably supported in a suitable housing (not shown) and having a finger 188 adapted to drive an operating bar 190 in a manner known to the art when the pull rod 186 is moved to the left as viewed in FIGURE 3. When this occurs, the operating bar pulls a link 192 to the left as viewed in FIGURE 3. A slot 194 in the link 192 receives a pin 196 carried by an arm 198 of a bellcrank 200 pivotally supported on a shaft 202 carried by the plate 12. A guide pin 204 carried by the plate 12 rides in a slot 206 in a bellcrank 200 to guide the crank in its movement. A pin 208 connects an arm 210 of bellcrank 200 to one end of a driving link 212 having a curved slot 214 which receives a pin 216 carried by the panel 12 to guide the link in its movement. The bifurcated end 218 of link 212 receives a pin 220 carried by a locking bar 222 adapted to be freed for movement upon the deposit in the machine of a sum in coins aggregating the purchase price of a selected article in a manner known to the art.

A pin 228 pivotally connects the locking bar 222 to an arm 224 rotatably supported on a shaft 226 carried by panel 12. When the bar 222 is freed and as rod 186 is moved to the left as viewed in FIGURE 3, it drives bar 190 and link 192 to rotate bellcrank 200 in a counterclockwise direction to move link 212 upwardly. Owing to the interaction of slot 214 and pin 216, the upper end 218 of link 212 moves locking bar 222 to the left to rotate arm 224 in a counterclockwise direction. Arm 224 carries a pin 230 adapted to engage a bifurcation 232 on an escrow bucket operating arm 234 rotatably supported on a shaft 236 carried by the panel 12 and the wall 36. A spring 238 surrounding the shaft 236 bears between a pin 240 carried by a wall 36 and a pin 242 on the arm 234 normally to position the arm as shown in FIGURE 1. When arm 234 is moved in a counterclockwise direction under the action of arm 224, a pin 244 on the arm engages a cam surface 246 of a bucket actuating member 248 to pivot the member in a counterclockwise direction on a shaft 250 carried by wall 36. A pin 252 pivotally connects member 248 with a link 254 connected to a crank 256 on shaft 100 by a spring 258 extending between a pin 260 riding in a slot 262 in link 254 and a pin 263 carried by the link.

When member 248 rotates in a counterclockwise direction, it pulls link 254 downwardly as viewed in FIGURE 2 to rotate crank 256 in a counterclockwise direction to move wall 96 away from wall 84 to permit coins in the bucket 82 to drop through an opening 264 formed on the side of boss 92 remote from opening 180 to a suitable coin box 266 disposed below the bucket. In the course of its movement downwardly, link 254 causes an offset portion 268 of the link to carry arm 48 away from the wall 36 to move the projection or lug 46 out of the path of a nickel on shaft portion 30 to permit the nickel to roll into the coin tube.

In operation of our coin bucket and escrow shelf, when a purchase is made on a machine provided with our assembly, coins deposited in the slot 24 pass through the coin separator and slug rejector 22 to the totalizer 26. The totalizer 26 operates in a manner known to the art to establish a credit corresponding to a sum in coins deposited in the machine. In the course of this operation, when a sum equalling at least the purchase price of an

article has been deposited, bar 222 is free to permit a purchase to be made and at the same time the change giving mechanism is conditioned to give a sum in change equal to the difference between the purchase price of a desired article and the sum in coins deposited in the machine.

- Coins of a denomination which is given in change, such for example as nickels, pass out of the totalizer 26 along the path indicated by broken lines in FIGURE 1. The first of these coins coming from totalizer 26 pivots feeler 32 in a clockwise direction as viewed in FIGURE 1 and comes to rest on the movable shelf portion 30 in which it is held by the lug 46. Nickels following the first nickel coming from the totalizer 26 cannot pivot the feeler 32 owing to the presence of the nickel on the movable shelf portion 30 and are directed by the feeler to the bucket 82. Dimes and quarters leaving the totalizer 26 along the path indicated by the dot-dash lines in FIGURE 1 fall into the bucket 82.
- When a purchase is made, bar 186 is moved to the left as viewed in FIGURE 3 to pull link 192 to the left to rotate bellcrank 200 in a counterclockwise direction to drive link 212 upwardly to cause its upper end to move bar 222 to the left. This movement of bar 222 rotates arm 224 in a counterclockwise direction to cause pin 230 to drive arm 234 in a counterclockwise direction. Upon this movement of arm 234, pin 244 engages the cam surface 246 to move member 248 in a counterclockwise direction. When this occurs, link 254 is pulled downwardly to rotate crank 256 in a counterclockwise direction to move wall 96 away from wall 84. When the bucket 82 opens in this manner, coins in the bucket fall down through opening 264 to the coin box 266. In the course of the movement downwardly of the link 254, the portion 268 of the link actuates arm 48 against the action of the spring carried by the hinge 50 to move stop 46 out of the path of the nickel on the movable shelf portion 30. This coin then rolls down track 55 to the coin tube 56.
- If a full supply is in the change coin tube 56, then the top coin in the tube actuates feeler 62 to move arm 58 to a position at which the stop 76 on the link 64 is in the path of movement of the lug 78 on the arm 80. In this position of the parts none of the nickels coming from the totalizer 26 are permitted to move onto shelf portion 30 but are all directed into the bucket 82.
- If after a sum in coins has been deposited in the slot 24 so that the first nickel has come to rest on the movable shelf portion 30 and the other coins have fallen into the bucket 82 and the purchaser wishes the coins returned, he pulls bar 116 to the left as viewed in FIGURES 1 and 4. Upon this operation of the bar, the coin return bellcrank 120 is driven in a clockwise direction as viewed in FIGURES 1 and 4 to move links 136 and 144 downwardly. This movement of the links causes link 150 to be moved downwardly to drive arm 170 in a counterclockwise direction to move crank 178 in a counterclockwise direction to pivot wall 84 and the movable shelf portion 30 to the broken line position shown in FIGURE 4.
- When this occurs, the nickel which had come to rest on the movable shelf portion 30 and coins caught in the bucket 82 fall downwardly and out through opening 180 to guide 182 which directs the coins to a coin return slot (not shown) at which they are accessible to the depositor. It is to be noted that since wall 84 is pivoted at its bottom while wall 96 is pivoted at the top, there is little danger that a coin will be caught between the walls.
- It will be seen that we have accomplished the objects of our invention. We have provided a coin shelf and escrow bucket which overcomes the deficiencies of coin mechanism of the prior art. Since our mechanism holds only a single coin of the denomination given in change in escrow for movement into the change coin tube when the coins are accepted, there is no danger that two thin coins of the kind given in change will cause

the machine to jam. The construction of our escrow bucket is such that there is little chance of a coin being trapped between the bucket walls. We have provided a very simple mechanism for returning both the change coin held in escrow and the coins in the escrow bucket to the customer in the event that the customer wishes the return of deposited coins.

It will be understood that certain features and sub-combinations are of utility and may be employed without reference to other features and subcombinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. In a merchandising machine having a first member movable in response to a dispensing operation of the machine and a second member adapted to be actuated to return deposited coins to a customer, an escrow bucket assembly including in combination a frame, a first bucket wall, means mounting said first bucket wall on said frame for pivotal movement about an axis generally parallel to the plane of said first wall and adjacent the upper end of the wall, a second coin bucket wall, means mounting the second wall on the frame for pivotal movement about an axis generally parallel to the plane of said second wall and adjacent the lower end thereof, said first and second walls being adapted to cooperate to form a pocket for the reception of coins deposited in the machine, means for biasing said walls to positions at which they cooperate to form said pocket, means responsive to movement of the first member for moving one of said walls about its axis to accept coins in said pocket and means responsive to actuation of the second member for moving the other wall about its axis to return said coins in said pocket.

2. In a merchandising machine having a first member movable in response to a dispensing operation of the machine and a second member adapted to be actuated to return deposited coins to a customer, an escrow bucket assembly including in combination a frame, a first bucket wall, means mounting said first bucket wall on said frame for pivotal movement about an axis adjacent the upper end of the wall, tongues formed in the lower end of said first wall, a second coin bucket wall, means mounting the second wall on the frame for pivotal movement about an axis adjacent the lower end thereof, openings formed adjacent the lower end of the second wall adapted to receive the tongues of said first bucket wall, said first and second walls being adapted to cooperate to form a pocket for the reception of coins deposited in the machine, means for biasing said walls to positions at which they cooperate with said tongues disposed in said openings, means responsive to movement of the first member for moving one of said walls about its axis to accept coins in said pocket and means responsive to actuation of the second member for moving the other wall about its axis to return said coins in said pocket.

3. In a merchandising machine having a first member movable in response to a dispensing operation of the machine and having a second member adapted to be actuated to return deposited coins to a customer and having a change coin reservoir, an escrow bucket and coin shelf assembly including in combination a frame, a first bucket wall, means mounting said first bucket wall on said frame for pivotal movement about an axis adjacent the upper end of the wall, a second coin bucket wall, means mounting the second wall on said frame for pivotal movement about an axis adjacent the lower end thereof, said first and second walls being adapted to cooperate to form a pocket with each other for the reception of coins deposited in said machine, a coin guide portion carried by said second wall, said coin guide portion being adapted to direct a

coin resting thereon toward said coin change reservoir, a stop for retaining a coin on said coin guide portion, means normally urging said walls to positions at which they form said pocket, means responsive to movement of said first member for pivoting said first wall away from said second wall and for rendering said stop inoperative and means responsive to actuation of said second member for pivoting said second wall and said coin guide portion away from said first wall to return coins to a customer.

4. In a merchandising machine having a first member movable in response to a dispensing operation of the machine and having a second member adapted to be actuated to return deposited coins to a customer, a coin mechanism including in combination a frame, a first bucket wall, means mounting said first bucket wall on said frame for pivotal movement about an axis adjacent the upper end of the wall, a second coin bucket wall, means mounting the second wall on said frame for movement about an axis adjacent the lower end of the second wall, said first and second walls being adapted to cooperate with each other to form a pocket for the reception of coins, a change reservoir, a coin guide portion carried by said second wall, said coin guide portion being adapted to direct coins to said coin reservoir when said second wall occupies its pocket forming position, a stop for retaining a coin on said coin guide portion, means for directing coins of the denomination to be given in change to said coin guide portion and for directing coins of other denominations to said pocket, means normally urging said walls to their pocket forming positions, means responsive to movement of said first member for moving said first wall away from said second wall and for releasing said releasable means and means responsive to actuation of said second member for moving said second wall and said coin guide portion away from said first wall.

5. In a merchandising machine having a first member movable in response to a dispensing operation of the machine and having a second member adapted to be actuated to return deposited coins to a customer, a coin mechanism including in combination a frame, a first bucket wall, means mounting said first bucket wall on said frame for pivotal movement about an axis adjacent the upper end of the wall, a second coin bucket wall, means mounting the second wall on said frame for movement about an axis adjacent the lower end of the second wall, said first and second walls being adapted to cooperate with each other to form a pocket for the reception of coins, a change coin reservoir, a coin guide portion carried by said second wall, said coin guide portion being adapted to direct coins to said coin reservoir when said second wall occupies its pocket forming position, means for directing coins of the denomination to be given in change to said coin guide portion and for directing coins of other denominations to said pocket, a stop for retaining the first coin of the denomination to be given in change on said coin guide portion, means for diverting coins of the denomination to be given in change following the first coin of such denomination into said pocket, means normally urging said walls to their pocket forming positions, means responsive to movement of said first member for moving said first wall away from said second wall and for releasing said releasable means and means responsive to actuation of said second member for moving said second wall and said coin guide portion away from said first wall.

6. In a merchandising machine having a first member movable in response to a dispensing operation of the machine and having a second member adapted to be actuated to return deposited coins to a customer, a coin mechanism including in combination a frame, a first bucket wall, means mounting said first bucket wall on said frame for pivotal movement about an axis adjacent the upper end of the wall, a second coin bucket wall, means mounting the second wall on said frame for movement

about an axis adjacent the lower end of the second wall, said first and second walls being adapted to cooperate with each other to form a pocket for the reception of coins, a change coin reservoir, a coin guide portion carried by said second wall, said coin guide portion being adapted to direct coins to said coin reservoir when said second wall occupies its pocket forming position, a stop for retaining a coin on said coin guide portion, means for directing coins of the denomination to be given in change to said coin guide portion and for directing coins of other 10 denominations to said pocket, means normally urging said walls to their pocket forming positions, means responsive to movement of said first member for moving said first wall away from said second wall and for releasing said releasable means, means responsive to actuation 15

of said second member for moving said second wall and said coin guide portion away from said first wall, means for sensing the presence of a full supply of coins in said change coin reservoir and means responsive to the operation of said sensing means for diverting coins of the denomination to be given in change into said pocket.
